THERMAL SWITCH AND RELAY

Joseph Schmidinger, Lake George, N. Y.

Original application August 11, 1939, Serial No. 289,529. Divided and this application April 20, 1942, Serial No. 439,740

18 Claims. (Cl. 200—137)

This invention relates to thermally controlled or operated switches.

This application is a division of application S. N. 289,529, filed August 11, 1939.

One object of the invention is a novel and improved thermal relay switch which is particularly adapted to use in the control and starting of fluorescent lamps, although it may be used for other purposes.

Further objects of the invention will herein-after appear.

For a better understanding of the invention reference may be had to the accompanying drawing forming a part of this application wherein:

Fig. 1 illustrates a circuit of a fluorescent lamp with one embodiment of my invention associated therewith;

Fig. 2 is a plan view of the switch unit;

Fig. 3 is a sectional view along the line 3—3 of Fig. 2;

Fig. 4 is a sectional view along the line 4—4 of Fig. 2 and the casing;

Fig. 5 is a sectional view along the line 5—5 of Fig. 2 and the casing;

Fig. 6 is an exploded view of a switch unit part.

Referring to Fig. 1 I have shown diagrammatically a fluorescent tube lamp 1 of the type which has now gone into commercial use, whose circuit embodies a condenser 2 and a choke coil 3, the condenser being connected between the filament electrodes and the coil being connected in series with the tube, the electric supply line being indicated at 4. In the particular embodiment shown, at starting or upon initial closure of the switch the condenser 2 is short circuited, and when the shunt or short circuit across the condenser 2 is quickly opened after the heating of the filaments the surge produced tends to assist in starting the discharge for the normal lighting operation of the lamp. The thermal switch unit 5 functions thus quickly to open the shunt across the condenser at starting with no or a minimum of make and break contacts at such operation, a minimum of surges and with the speed desired in practice.

The switch unit 5 comprises a pair of terminals 6', 7' connected by the lines indicated to the opposite sides of the condenser 2 and a second pair of terminals 8' and 9' for connecting the unit in the circuit. The terminals 6' and 7' lead respectively to contacts 10 and 11 which are closed when the line circuit is open. The contact 10 is carried by a lug 12 which is stamped from a sheet metal piece 6 from which the

terminal 6' is integrally formed. The contact 11 is carried by a buckled and constrained strip or vane 13 which is fastened at its ends to a sheet metal piece 7. In the mounting of this buckled strip 13 upon the sheet metal piece 7 it is put under constraint so as to tend to separate the contact 11 from the contact 10, and an expandible wire 14 is attached to the vane 13, as for example through the angle piece 15 which is fastened to the vane 13 adjacent one end thereof, so as to oppose and overcome the tendency of the vane 13 to withdraw the contact 11. The wire 14 passes through an eyelet of the angle piece 15 and has fixed thereto a glass bead 16 resting in the eyelet and the vane is preferably reduced in width as indicated at 13', as set forth in the above patent.

The frame or mount for this switch comprises a multiplicity of flat metallic plate members 7, 20 6, 9 and 8 with interposed flat insulating sheet or plate members 17 and 18. The insulating plate member 17 is interposed between the metallic plate 7 on the one hand and the plates 6 and 9 on the other and the insulating plate 18 is interposed between the metallic plates 6 and 8. All these plates are clamped together by the pairs of lugs 20 and 21 formed on the sides of the plate 7 which lugs are first bent at right angles to the plate 7 and then after the assembly of the plates together they are crimped around underneath in the form of U's to firmly hold the plates against lateral separation. The insulating plate 17 is similarly formed with pairs of lugs 20' and 21' and the plate 17 is slightly narrower than the plate 7 so as to nest therein with the lugs 20 and 21 being disposed on the outside of the lugs 20' and 21'. When the lugs 20 and 21 are crimped or folded under to hold the other plates firmly against the plate 17 the lugs 20' and 21' are similarly crimped or folded under, the lugs 20' being disposed between the plate 9 and the lugs 20 of plate 7 and the lugs 21' engaging the under side of the plate 8 and there held by the lugs 21. The plate 7 is provided with down turned edges 22 disposed between the lugs 20 and 21 and the insulating plate 17 is provided with a similar turned down edge 22'. The plates 6 and 9 nest in between the down turned edges 22' of the plates 17.

40 The insulating plate 17 is provided with an elongated upstanding lug 24 at one end and an angle arm 25 is formed on the end of this lug, this angle arm 25 having a notch 25' for the reception of the wire 14 leading from the bead 16. The wire is then carried back and electrically

welded or otherwise fastened to an upstanding lug 26 which is formed integrally with the plate 8. The other end of the wire 14 is fastened to a small rotary shaft or pin 27 which is mounted for rotary adjustable movement in a bearing member 28 formed integrally with the plate 9, this bearing member 28 being formed by upsetting the end of the plate 9 90° and then bending the top back upon itself to form an eyelet 28' for the reception of the adjustable pin 27 in a tight frictional grip against turning in response to wire tension. This pin or shaft is rotated for adjusting the tension of the wire 14, the adjustment being conveniently effected by engaging the right angle end 27' of the pin 27 by means of any convenient tool. The bearing member 28 projects up through a notched or cut-out portion 30 formed in the end of the insulating plate 17, the bottom of this notch projecting out beyond the end of the plate 7 so as to space the bearing 28 from the plate 7. The lug 26 in the assembled position engages the elongated lug 24 of the insulating plate 17. The plate 6 is provided with a cut-out portion 31 at its inner end and the lug 12 projects outwardly through this notch or cut-out 31, the lug 12 having its inner portion reduced in width as indicated at 32. The lug 12 is also provided with a downturned end 12' with an opening 33 therethrough for facilitating the adjustment of the contact 10. This may be adjusted by the use of any suitable tool for engaging and bending the lug 12. The plate 9 is also formed with a notch or cut-out portion 34 for clearing the lug 12 and the plates 7 and 17 are provided with central rectangular openings 35 for accommodating the lug 12 and vane 13 and their contacts 10 and 11.

After the switch structural elements are assembled, as indicated in Figs. 2 and 3, the whole unit may be positioned in a suitable container such as the insulating carton 36, with the terminals 6', 7', 8' and 9' projecting out through openings formed in the covers 36' thereof. After such assembly the terminal 6', 7', 8' and 9' may be bent over at right angles as indicated in Fig. 1 in which position they hold the covers 36' in closed relation on the carton.

I claim:

1. A switch unit of the character set forth comprising a series of alternating metallic and insulated plates secured flat against each other, one of said metallic plates carrying a vane type switch member and another of said metallic plates carrying a contact member for cooperation with said vane member, certain of said metallic plates carrying circuit terminals for connecting the switch unit in circuit and certain of said plates having lugs folded under against the bottom plate to hold the plates tightly against each other.

2. A switch unit of the character set forth comprising a series of alternating metallic and insulated plates secured flat against each other, one of said metallic plates carrying a vane type switch member and another of said metallic plates carrying a contact member for cooperation with said vane member, and an expansible wire mechanically fastened to but insulated from said vane for operating said vane from one position to another, said wire being electrically and mechanically connected to a metallic plate which is insulated from the plates carrying the vane switch contacts.

3. A switch unit of the character set forth

comprising four metallic plate members, the second and third plate members being disposed in the same plane and spaced from the first plate member by an insulating plate, and a second insulating plate member disposed between the second metallic plate member and the fourth metallic plate member, the said plate members being secured flat against each other and carrying a thermally operated switch.

4. A switch unit of the character set forth comprising four metallic plate members, the second and third plate members being disposed in the same plane and spaced from the first plate member by an insulating plate, and a second insulating plate member disposed between the second metallic plate member and the fourth metallic plate member, the said plate members being secured flat against each other and carrying a thermally operated switch, the first metallic plate and the first mentioned insulating plate member being provided with registering openings, and said thermally operated switch comprising a vane member carried by the first metallic plate member in bridging relation to the opening formed therein and a cooperating contact member carried by the second metallic plate member.

5. A switch unit of the character set forth comprising four metallic plate members, the second and third plate members being disposed in the same plane and spaced from the first plate member by an insulating plate, and a second insulating plate member disposed between the second metallic plate member and the fourth metallic plate member, the said plate members being secured flat against each other and carrying a thermally operated switch, the first metallic plate and the first mentioned insulating plate member being provided with registering openings, and said thermally operated switch comprising a vane member carried by the first metallic plate member in bridging relation to the opening formed therein, a cooperating contact member carried by the second metallic plate member, and an expansible wire mechanically fastened to said vane but insulated therefrom, said wire being also mechanically fastened to the third metallic plate.

6. A switch unit of the character set forth comprising four metallic plate members, the second and third plate members being disposed in the same plane and spaced from the first plate member by an insulating plate, and a second insulating plate member disposed between the second metallic plate member and the fourth metallic plate member, the said plate members being secured flat against each other and carrying a thermally operated switch, the metallic plate members being provided with integral terminals and said first named insulating plate being provided with a wire guiding means and the fourth metallic plate being provided with a lug for electrical connection with the wire.

7. A switch unit of the character set forth comprising four metallic plate members, the second and third plate members being disposed in the same plane and spaced from the first plate member by an insulating plate, and a second insulating plate member disposed between the second metallic plate member and the fourth metallic plate member, the said plate members being secured flat against each other and carrying a thermally operated switch, the first metallic plate and the first named insulating plate being provided with lugs on the sides thereof

which are folded under and hold the other plates tightly flat against each other.

8. A switch unit of the character set forth comprising a series of alternating metallic and insulated plates secured flat against each other, one of said metallic plates carrying a vane type switch member and another of said metallic plates carrying a contact member for cooperation with said vane member, an expansible wire mounted on one of said plates one of the plate members being provided with a bearing member and an adjustable rotary pin for the fastening and tightening of the expansible wire.

9. A switch unit of the character set forth comprising a series of alternating metallic and insulated plates secured flat against each other, one of said metallic plates carrying a vane type switch member and another of said metallic plates carrying a contact member for cooperation with said vane member, comprising a carton housing with covers having openings formed therein and said metallic plates being provided with terminals projecting through said openings of the covers and bent thereabout to hold the switch unit carton and covers in assembled relation.

10. A switch unit of the character set forth comprising a metallic plate, an insulating plate, a second and third metallic plate, a second insulating plate and a fourth metallic plate, all of said plates being secured flat against each other by means of lugs formed on the sides of said first named metallic plate and said first named insulating plate and folded and crimped thereunder, said metallic plate members having terminals projecting therefrom, said first named plate carrying a thermostatically operated vane switch member, said second named plate carrying a cooperating switch contact in the form of an adjustable tongue struck therefrom, said third named metallic plate having a notch formed adjacent said tongue for accommodating the same and also having a bearing member and an adjustable pin member for an expansible wire, said first named insulating plate having a notch for accommodating said bearing member and spacing the same from the first named metallic plate, and said fourth metallic plate having a lug forming a means for electrically attaching an expansible wire to said plate, said first named insulating plate having an elongated lug disposed between the first named metallic plate and said lug formed on the fourth metallic plate.

11. A switch unit of the character set forth comprising a plurality of metallic and insulated plate members, two of said metallic plate members being disposed in the same plane and spaced from other of said metallic members by said insulated plate members, means carried by certain of said plate members for holding all the plate members flat against each other and a thermally operated switch carried by said plate members.

12. A switch unit of the character set forth comprising a series of alternating metallic and insulated plates secured flat against each other, one of said metallic plates carrying a vane type switch member and another of said metallic plates carrying a contact member for cooperation with said vane member, the top plate being provided with lugs which are folded under the bottom plate to hold the assembly tightly together.

13. A switch unit of the character set forth comprising a series of alternating metallic and insulated plates secured flat against each other, one of said metallic plates carrying a vane type switch member and another of said metallic plates carrying a contact member for cooperation with said vane member, and electrical means for controlling said vane switch, said metallic plates being provided with an integrally formed terminal member, and said terminal members forming electrical connections for said vane type switch and for said electrical means.

14. A switch unit of the character set forth comprising a series of alternating metallic and insulated plates secured flat against each other, one of said metallic plates carrying a vane type switch member and another of said metallic plates carrying a contact member for cooperation with said vane member, and electrical means for controlling said vane switch, there being four metallic plates and each having an integrally formed terminal member two of said terminals forming electrical connections for said vane switch and two electrical connections for said electrical means.

15. A switch unit of the character set forth comprising a series of alternating metallic and insulated plates secured flat against each other, one of said metallic plates carrying a vane type switch member and another of said metallic plates carrying a contact member for cooperation with said vane member, an expansible wire operatively connected with said vane switch, and one of said insulating plates having a wire guiding lug integrally formed thereon.

16. A switch unit of the character set forth comprising a series of alternating metallic and insulated plates secured flat against each other, one of said metallic plates carrying a vane type switch member and another of said metallic plates carrying a contact member for cooperation with said vane member, one of said insulating plates having side folded under parts to insulate similar side folded parts formed on a metallic plate.

17. A switch unit of the character set forth comprising a series of alternating metallic and insulated plates secured flat against each other, one of said metallic plates carrying a vane type switch member and another of said metallic plates carrying a contact member for cooperation with said vane member, the top plate being provided with lugs which are folded under the bottom plate to hold the assembly tightly together and the top insulating plate being provided with folded under parts to insulate the lugs from the plate immediately thereabove.

18. A switch unit of the character set forth comprising a plurality of metallic and insulated plate members, two of said metallic plate members being disposed in the same plane and spaced from other of said metallic members by said insulated plate members, means carried by certain of said plate members for holding all the plate members flat against each other and a thermally operated switch carried by said plate members, said thermally operated switch comprising a vane and an expansible wire operatively connected with said vane and fixedly connected with one of said plates.

JOSEPH SCHMIDINGER.
